UNITED STATES PATENT OFFICE.

WILLIAM A. BUSIEK, OF BELLEVILLE, ILLINOIS.

RANGE.

Application filed January 31, 1924. Serial No. 629,618.

To all whom it may concern:

Be it known that WILLIAM A. BUSIEK, a citizen of the United States of America, residing at Belleville, in the county of St. 5 Clair and State of Illinois, has invented certain new and useful Improvements in Ranges, of which the following is a specification.

The object of my invention is to make a 10 gas range and broiler, said range having a damper secured therein and having means for detecting nasally when the operator has placed the range in operation but failed to maintain the damper in an open position.

15 In the operation of a range, it is desirous that the products of combustion circulate through the range and pass out from the range into the flue. It is necessary to have a damper in this path of circulation. This

20 damper should be open to various degrees depending upon the heat desired in the range. It should never be absolutely closed when the range is in operation. My range provides means by which the operator will

25 discover when the range is in operation that the damper has been inadvertently kept in a closed position by conducting the fumes from the range into the room in which the range is operating and thereby notifying

30 the operator that the damper should be opened. The odor of the fumes is sufficient to give this alarm. I furthermore desire to attach a broiler to the range so that the products of combustion may be passed

35 through the circulatory system of the broiler thereby heating it.

With these and other objects in view, my invention has relation to certain novel features of construction and arrangements of 40 parts as will be hereinafter more fully described, pointed out in the claims and illustrated in the drawings in which—

Fig. 1 is a longitudinal sectional elevation of my device,

45 Fig. 2 is a sectional plan of my device.

The range 3 consists of the base 4, the front wall 5, the rear wall 6 and the side walls 7 and 8. The range is mounted on the legs 9 in the conventional manner. Numerals 10 designate the gas burners of conventional construction and numeral 11 the oven having the floor 12 and the sides 13. Numeral 14 designates the flue which is in fluid communication with the opening 15 in the oven. Numeral 16 designates the top of the range and numeral 17 the top of the

oven. The top of the range and the top of the oven are secured in spaced relationship as best shown in Fig. 1 to the side walls 7 and 8 and to the front wall 5. The top of the range is also secured to the rear wall 6. Numeral 18 designates the back of the oven and extends from the top of the oven 17 to the base 4 to which it is secured. It is also secured to the side walls 7 and 8. 60 Numerals 19 designate perforations in the back of the oven 18 above the top of the oven 17. The circulation of the products of combustion is indicated by arrows. The circulation for which has been provided thus far is as follows: The cold air enters 70 through perforations in the base 4 not shown, passes laterally by the burners 10 where it is heated and then passes upwardly between the sides 13 of the oven 11 and the side walls 7 and 8 of the range over the top of the sides 13 into the oven, through the opening 15, into the flue 14 upwardly 75 into the space above the top of the oven 17 and below the top of the range 16 through 80 the perforations 19. The products of combustion are now in the space between the top of the range 16 and the top of the oven 17 in front of the back of the oven 18. Numeral 20 designates a baffle plate secured 85 to the top of the oven 17 and to the top of the range 16 longitudinally and having its one end secured to the back of the oven 18. This baffle plate 20 is positioned at the angle indicated in Fig. 2. Numeral 21 designates 90 the smoke stack secured to the rear wall 6 of the range. The sides of the smoke stack 21 are continued from the rear wall 6 to the back of the oven 18 as best shown in Fig. 2. They are secured at their top to the top of 95 the range 16 and at their bottom to the top of the oven 17. An opening 22 is formed in the back of the oven 18 between the wall continuations of the smoke stack 21 just indicated. It will be seen that by these 100 means fluid communication is established between the smoke stack 21 and the space between the top of the oven 17 and the top of the range 16 to the right of the baffle plate 20 in Fig. 2. The products of combustion may now after passing through the perforations 19 in the back of the oven 18 pass around the baffle plate 20 as indicated by the arrows in Fig. 2 and then into the opening 22 and thence into the smoke stack 21. 105 Numeral 23 designates a hinged damper hingedly secured to the back of the oven 18 110

by the hinges 24 and 25. Numeral 26 designates an eye secured to the damper and numeral 27 a damper rod having a hook at its one end, which hook passes through the eye 26. The external end of the damper rod 27 passes through the front wall 5 and terminates in the knob 28. It will be seen that by moving the knob forwardly and rearwardly that the damper 23 will be 10 opened and closed. For the purpose of securing the damper 23 in any given selective position notches 29 may be formed on the damper rod 27, which notches may be hooked into the opening in the front wall 5. Applicant has attempted to describe a simple conventional damper and claims no novelty in the damper. The side wall 8 terminates at 30 leaving an opening between it and the end of the back of the oven 18. Numeral 31 20 designates a broiler which is simply shown in outline because applicant claims no novelty in it per se. The broiler 31 may be made as shown in rectangular form and secured to the range wall 8 integrally or in 25 any other manner with the top of the broiler 31 being a continuation of the top of the range 16. In the rear wall near the upper left hand corner as indicated in Fig. 1 are formed perforations 32. It will be seen that 30 the products of combustion if the damper 23

is closed will be forced to pass through the opening between the end 30 of the wall 8 and the back of the oven 18 into the broiler 31 into the atmosphere exterior to the range and broiler through the perforations 32. 35 The circulation of the products of combustion in the broiler is shown by the arrows in the broiler in Fig. 1. When the damper is open the draft will be sufficient to cause the products of combustion to pass by the 40 opening into the broiler into the smoke stack 21. The products of combustion will, therefore, only pass into the broiler 31 when the damper 23 is closed.

What I claim and mean to secure by Letters Patent is—

In combination with a range, a damper positioned in the path of the products of combustion and means for directing the products of combustion exteriorly relative 50 the range when the damper is in a closed position, a broiler secured to said range, the broiler and range being in continuous fluid communication in the path of the products of combustion through the range and means for directing indirectly the products of combustion from the range to the broiler.

In testimony whereof I affix my signature.

WILLIAM A. BUSIEK.
